Primary Examiner — Patricia A Palasik(74) *Attorney, Agent, or Firm* — Foley & Lardner LLP(57) **CLAIM**

We claim the ornamental design for an actuator, as shown and described.

DESCRIPTION

FIG. 1 is a top, front, left perspective view of the claimed actuator;

FIG. 2 is a bottom, rear, right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Any portion of the article depicted in broken lines forms no part of the claimed design.

1 Claim, 8 Drawing Sheets(56)
